UNITED STATES PATENT OFFICE.

LEON COHEN, OF ST. LOUIS, MISSOURI, ASSIGNOR TO DE LEON BANDEAUX CO., OF ST. LOUIS, MISSOURI, A CORPORATION OF MISSOURI.

DETACHABLE HAT PAD.

Application filed May 28, 1923. Serial No. 641,864.

To all whom it may concern:

Be it known that I, LEON COHEN, a citizen of the United States, and resident of the city of St. Louis, and State of Missouri, have invented certain new and useful Improvements in Detachable Hat Pads, of which the following is a specification, containing a full, clear, and exact description, reference being had to the accompanying 10 drawings, forming a part thereof.

My invention relates to improvements in detachable hat pads and has for its primary object a device for reducing the sizes of hats in the rear portion thereof, and making 15 the hat fit the front portion of the forehead snugly without affecting the appearance of the hat on the head of the wearer.

In the drawings:

Fig. 1 is a perspective view looking up 20 in the inside of a hat showing my invention applied for use in the rear portion thereof;

Fig. 2 is an enlarged cross section of my 25 invention taken through one of the fastening prongs;

Fig. 3 is a perspective view of one of the 30 sleeves and prongs carried thereby;

Referring to the drawings, 4 indicates a thin metal flexible strip of spring material which I employ in the construction of my 35 device. This strip is of a length slightly longer than half of the inside circumference or perimeter of the hat crown so that when the same is sprung into position, it will not spring out and become accidentally detached from the hat. 5 indicates sleeves which are applied to the metal strip 4, and these sleeves are provided with prongs 6. 7 indicates a body of fibrous material which is enclosed in a casing 8 so as to form a 40 relatively thick resilient packing or cushion. After the fibrous material has been incased in its casing 8, it is placed against the face of the metal strip 4 on the face opposite to the prongs. I then apply over 45 the metal strip and the incased body of fibrous material a flexible piece of fabric and sew the edges thereof together so as to form a flexible tube or outer casing 9. Before I stitch the edges of the outer casing 50 or tube lining together, the prongs 6 are forced through the material out of which said outer casing is made.

The material out of which the outer casing is made, is fit snugly on the outer 55 surface of the metal strip so that when the de-

vice is applied in a hat crown, it will fit closely against the inside thereof and the prongs extend into the hat lining and material of which the hat is made.

I may, if desired, omit the casing around 60 the body of fibrous material and employ only the flexible metal strip and a body of fibrous material and the outer casing.

After my device has been constructed as 65 previously described, it is applied to the rear portion of the inside of a hat, as illustrated, by inserting the prongs 6 in the hat without the use of sewing or any other fastening means. By this construction it is to be noted, that my device may be easily 70 removed, and only one pad need be purchased as the same can be readily and quickly applied to different hats.

It will further be observed, that the fibrous yielding member 7 is relatively thick 75 and being loosely packed, will adjust itself without any undue pressure to the head of the wearer.

While I have shown and described the 80 outer casing 9 as being a piece of fabric sewed together along its edges so as to form a tube, it is obvious that the casing 9 may be woven in tubular form. When constructed in this manner the tube is first 85 slipped over the metal strip 4, after which the prongs 6 are forced through the material and then the fibrous pad inserted in position, after which the ends are closed in any well known manner. It will be observed from Fig. 2 the the casing 8 not only 90 acts as a support or backing for the fibrous material at the rear but it also acts as a support or rest for the thin elastic strip 4.

Having fully described my invention, 95 what I claim is:—

1. A detachable hat pad comprising a flexible spring metal strip, prongs carried thereby and projecting from the outer surface of said strip, a body of relatively thick fibrous material placed against the inner 100 face of said metallic strip, and a body of fabric passed around said metal strip and said body of fibrous material, and the edges of the fabric united together by stitching and having the prongs extended there- 105 through.

2. A detachable hat pad comprising a flexible spring metal strip of a length slightly greater than half the circumference 110 of the hat to which the device is applied, de-

- attachable prongs projecting from the exterior surface of said metallic strip, a body of incased fibrous material of substantially the same length as the metallic strip and located 5 on the inner face of said strip, a strip of fabric secured to the outer face of said metallic strip by means of projecting the prongs through said strip and passed around and enclosing said metallic strip 10 and said body of incased fibrous material, and having its edges united and ends closed.
3. A detachable hat pad comprising a flexible spring metal strip of a length slightly greater than half the circumference 15 of the hat to which the device is applied, prongs projecting from the exterior surface of said metallic strip, a body of incased fibrous material of substantially the same length as the metallic strip and located on 20 the inner face of said strip, a strip of fabric secured to the outer face of said metallic strip by means of projecting the prongs thereof through said fabric and passed around and enclosing said metallic strip 25 and said body of incased fibrous material, and having its edges united and ends closed.
4. A detachable hat pad comprising a flat strip of spring material, a plurality of prongs carried thereby in spaced apart position and projecting from one face thereof, and a resilient piece of fibrous material located on the face of the said strip opposite said prongs, said strip and fibrous material being of less length than the inside circumference 35 of the crown of a hat.
5. The hat pad of claim 4 in which a closed fabric covering is provided for the flat strip and fibrous material, and through which the prongs project so as to permit 40 engagement with the crown of a hat.
6. A detachable hat pad comprising a flexible spring metal strip, a prong carried thereby and projecting from the outer surface of said strip, a body of relatively thick 45 fibrous material located on the side of said strip opposite said prong, and a body of

fabric passed around said fibrous material and resting against and secured to one face of said strip, said strip and fibrous material being of less length than the inside circumference of the crown of a hat to which it is applied. 50

7. A hat size reducer comprising a strip of flexible spring material provided with prongs for detachably securing the same 55 within a hat crown, a flexible casing surrounding said strip of spring material and held in place by passing the prongs therethrough, and a piece of yielding material adapted to reduce the head receiving opening of a hat secured within said flexible casing and covered thereby, said strip and yielding material being of less length than the inside circumference of the hat crown. 60

8. A hat size reducer comprising a strip of flexible spring material, a plurality of prongs carried thereby, and a resilient piece of fabric incased material arranged on the inside of said strip and held in position by the prongs passing through the fabric for 65 reducing the head receiving opening of a hat crown, said strip and fabric incased resilient material being of less length than the inside circumference of the hat crown. 70

9. A detachable hat pad comprising an elastic strip, a prong carried thereby and projecting from one face thereof, a body of relatively thick fibrous material located on the inside face of said strip opposite said prong, a flexible backing member for the 75 fibrous material at its rear and acting as a support for the elastic strip, and a body of fabric passed around said fibrous material and resting against and secured on one face of said strip, said strip and fibrous material being of less length than the inside circumference of the crown of a hat to which it is applied. 80

In testimony whereof, I have signed my name to this specification. 85

LEON COHEN.
